UNITED STATES PATENT OFFICE

RYUJI SATO, OF NEW YORK, N. Y.

HERMETIC TUBE CLOSURE

Application filed June 24, 1929. Serial No. 373,116.

This invention relates to closures for collapsible tubes and the like and has special reference to a closure so arranged that when the tube is closed it is airtight, the device being preferably termed, on this account, a hermetic tube closure.

One important object of the invention is to provide a simple and efficient device having improved means for closing the delivery end 10 of a collapsible tube and the like in such manner that when closed the tube will be airtight.

A second important object of the invention is to provide an improved closure of this 15 class wherein a cap is used which carries a collapsible washer so arranged that when the cap is moved to closed position the washer is compressed against the opening into the tube.

20 A third important object of the invention is to provide an improved closure of this description wherein the collapsible washer is maintained in proper position in a simple and efficient manner.

25 With the above and other objects in view as will be hereinafter apparent, the invention consists in general of certain novel details of construction and combinations of parts hereinafter fully described, illustrated 30 in the accompanying drawings and specifically claimed.

In the accompanying drawings like characters of reference indicate like parts in the several views, and:

35 Figure 1 is a side elevation of the neck or delivery end of a collapsible tube showing the improved closure thereon.

Figure 2 is an end view of Figure 1.

40 Figure 3 is an enlarged detail transverse section on the line 3—3 of Figure 2.

Figure 4 is an enlarged bottom or inside view of the cap.

In the embodiment of the invention herein 45 illustrated there is shown a collapsible tube 10 having the usual frusto-conical end 11 and centrally of this end extends a tubular neck 12 provided with external screw threads 13. Across the mouth end of the neck 12 extends a fixed partition 14 so arranged that an opening 15 is left at one side between the wall

of the neck and an edge portion of this partition.

To cover and close the opening 15 there is provided a cap having a body 16 and from this body extends a flange 17 of annular form 55 and threaded internally to engage the threads 13, the flange being cut away as at 18 to form a notch, the ends of which are selectively engageable with a pin 19 projecting from the neck 12 so that rotation of the cap is limited 60 in accordance with the length of the notch 18. By reason of the provision of the flange 17 the cap is thus formed with a recess in its underside and an opening 20 extends from the top face of this cap adjacent one edge and 65 opens into the recess in the lower side of the cap. This opening is so arranged that it is of segmento-circular cross-section and may be rotated into and out of registry with the opening 15, right handed rotation moving it out 70 of registry and left handed rotation moving it into registry. Across the recess in the cap at the edge of the opening 20 extends a rib 21 which thus divides the recess into two parts, the opening 20 communicating with 75 one part and the other part of the recess being filled with a washer 22 of cork, rubber, or other like compressible material which extends slightly below the lower edge of the rib 21 so that as the cap is rotated in a right 80 handed direction to move the opening 20 out of registry with the opening 15 the washer 22 is moved to cover the opening 15 and, by reason of the screw threads, is compressed 85 against this opening so as to close it hermetically and thus render it airtight. It will be observed that by the provision of the rib 21 the washer 22 cannot slip around out of place but is always in proper position inside 90 of the cap.

In operation, of course, when it is desired to permit the contents of the tube to flow out the cap is moved to bring the openings 15 and 20 into registry while at other times the washer is screwed down on the opening 15.

There has thus been provided a simple and efficient device of the kind described and for the purpose specified.

It is obvious that minor changes may be 100 made in the form and construction of the in-

vention without departing from the material spirit thereof. It is not, therefore, desired to confine the invention to the exact form herein shown and described, but it is desired to include all such as properly come within the scope claimed.

Having thus described the invention, what is claimed as new, is:

10 In a collapsible tube, a neck having a screw threaded exterior, a partition extending across the neck and having an opening adjacent one side of the neck, a cap having a body portion and provided with an annular flange screw threaded interiorly to fit the neck, the space within the flange constituting a recess, said body having an opening extending from the outer surface of the top and communicating with the recess, a rib extending across said recess adjacent the opening 20 of the top, an elastic washer held in the recess between the rib and the wall of the recess, said openings being movable into and out of registry by rotation of the cap and the washer being compressed over the first opening 28 by the action of said screw threads upon the openings being moved out of registry, said flange having an arcuate notch therein at its lower edge, and a pin projecting from the neck into said notch to limit rotative movement of the cap.

In testimony whereof I affix my signature.
RYUJI SATO.
